UNITED STATES PATENT OFFICE.

MATTHEW C. OSTER, OF ROY, MONTANA.

GATE AND DOOR OPERATING MECHANISM.

1,380,077.

Specification of Letters Patent. Patented May 31, 1921.

Application filed June 7, 1919. Serial No. 302,449.

To all whom it may concern:

Be it known that I, MATTHEW C. OSTER, a citizen of the United States, residing at Roy, in the county of Fergus and State of 5 Montana, have invented certain new and useful Improvements in Gate and Door Operating Mechanism, of which the following is a specification.

The present invention relates to operating 10 mechanism for gates and doors adapted to automatically open the gate or door upon the approach of a vehicle therethrough and the passage of the vehicle through the gate or door opening.

15 An object of the present invention is to provide such mechanism; to provide a mechanism wherein the gate or door can be opened only at the approach of a vehicle wherein a pair of gate or door members are provided and wherein the members cannot be independently opened, where the shock incident to the automatic opening of the gate or door members is absorbed or checked at the extreme end of the opening and closing movement of the gate or door members, wherein vibration is reduced to a minimum, and wherein the full and complete operation of opening or closing of the mechanism is insured.

30 Another object of the present invention is to provide a novel means for automatically latching together a pair of gate or door members and the provision of the means associated with the automatic operating 35 mechanism for initially releasing the latches prior to the opening operation and for initially setting the latches immediately subsequent to the final closing operation of the gate or door members.

40 The above, and various other objects and advantages will be part described in and in part understood from the following detailed description of the present preferred embodiment, the same being illustrated in the accompanying drawings, wherein;

45 Figure 1 is a side elevation of a wall or fence provided with gates or doors and operating means and latch mechanism constructed according to the present invention applied thereto.

50 Fig. 2 is an outer end view of one of the gates or door members mounted upon the wall, parts of the apparatus being shown in section.

55 Fig. 3 is a fragmentary enlarged side elevation of the wall at one side of the gate or

door opening, showing one closure member partially open, the dotted lines illustrating the closure member in full open position, and with the mechanism adjusted accordingly.

Fig. 4 is a fragmentary enlarged sectional view through the cushioning or shock absorbing device employed, illustrating the connection to the operating mechanism.

Fig. 5 is a fragmentary enlarged sectional view through one side of the gate or door frame, showing the operating mechanism mounted therein.

Fig. 6 is a detail perspective view of one of the latches employed on the gate or door.

Referring to the drawings, wherein the present embodiment of this invention is illustrated, as applied to a pair of gate sections mounted on a fence wall, 10 designates 75 the wall of the fence which is provided with a gate opening adapted to align with a roadway or the like and which is provided at opposite sides of the opening with posts or frame members 11. The wall 10 is also provided with posts 12 which are spaced from the posts 11 and which may be termed the outer posts, utilized for supporting the gate members or sections when the latter are moved staggeredly or retracted into open 80 position. The posts 11 and 12 are provided, near their upper ends with horizontally alining rollers 13 employed for slidingly supporting the door or gate sections upon the wall 10.

90 In the present instance the gate or door is formed in two parts or sections, the same being identical in construction and each provided with an elongated channel bar 14 having the facial portion thereof arranged vertically and with the flanges adapted to extend inwardly toward the adjacent side of the wall 10 and to receive therebetween the adjacent supporting rollers 13. The bar 14 is of a length equal substantially to twice 95 that of the body portion of the gate for supporting the latter in upright position and from tilting when extended into the gate or door opening beyond the adjacent post 11. The bar 14 comprises the upper 100 portion of the gate member, and the lower portion thereof is in the form of a substantially S-shaped bar 15 of a length slightly greater than that of the body of the gate and which is adapted to engage at its lower 105 end portion upon a roller 16 carried upon the adjacent side of the gate post 11. The 110

inner ends of the upper and lower bar 14 and 15 are rigidly connected together by means of a brace bar 17 extending diagonally downwardly and forwardly from the 5 inner end of the upper bar 14 to the inner end of bar 15. The body portion of the gate is in the form of a substantially rectangular frame 18 which may be of tubular or other suitable construction and which is provided 10 with any desired number of vertical strands 19 and horizontal braces or bars 20, in the present instance one transverse bar being shown, the same being arranged substantially between the upper and lower portions 15 of the gate body 18 and suitably secured to the frame 18 for connection of the operating mechanism therewith. It will be noted that each frame may be provided between the inner and outer ends with a 20 vertical supporting rod or portion 21 to which the bars 14, 20 and 15 are suitably connected. The rollers 13 on the wall 10 are adapted to engage between the flanges of the upper bar 14 and to thus not only 25 support the gate section but to also hold the section from tilting or extending about the rollers 13 located upon the outer post 12 and the rollers 13 arranged upon the inner post 11. The S-shaped bar 15 is arranged 30 with its upper flange section secured against the inner side of the gate body 18 and with its lower flange offset inwardly toward the wall 10 and adapted to rest in the roller 16, the latter being preferably grooved for maintaining the lower portion of the gate adjacent the walls. 35

The means employed for automatically opening and closing the gate sections is identical at opposite sides of the gate opening and each comprises round shaft 22 journaled in brackets 23 secured in spaced apart relation upon the outer side of the post 11, the round shaft 22 being provided upon its outer end adjacent the gate section with an 40 operating arm 24 adapted to swing to opposite sides of its pivotal support in the brackets 23. The arm 24 is connected by a link 25 to the adjacent gate members intermediate its top, bottom and inner and outer 45 edges thereof, such connection being affected by a pin 26 projecting from the crossed portions of the vertical bar 21 of the horizontal bar 20 and pivotally connected to one end of the link 25. The other end of the link 25 50 has pivotal connection at 27 to an intermediate portion of the operating arm 24. It will be noted that the link 25 is connected to the outer side of the operating arm 24 so that the latter, while swinging from one 55 side to the other side of the vertical plane of the pivot permits the free passage of the link 25 relatively to the end of the rock shaft 22.

The gate section is normally held extended or in closed position by the weight 60

28 which is suspended upon a rod 29 in a well or sunken casing 30 arranged at the outer side of the post 11. The rod 29 is pivotally connected to the outer end of a lever 31 provided with a hub portion 32 at 70 its inner end adapted to be adjustably fixed upon the rocker shaft 22 by a set screw 32 and which is a projection 33 extending from the hub portion diametrically opposite the arm 31. The projection or short arm is connected by a link 34 to a depressible element such as a beam 35 arranged transversely across the roadway beneath the surface thereof and extending between the posts 11 the connectors 34 being pivotally or otherwise suitably secured to the opposite ends of the depressible member 35. 75

While the depressible member 35 is connected at opposite ends to both of the gate member operating mechanisms, it is essential to exert uniform pressure upon the opposite end portions of the member 35 in order to simultaneously actuate the operating mechanisms to effect the uniform opening of the gate members. To produce this 80 result the mechanism is provided at opposite sides of the walls 10 with outwardly extending and suitably spaced apart spreads or runways 36 which are spaced apart a distance substantially equal to the tread of 85 vehicles adapted to pass through the gate or door opening, and which have their inner ends meeting and resting upon the transversely adjustable member 35 integrally beneath the gate or door opening. The outer 90 ends of the runway 36 are pivotally supported upon rails or blocks 37 which are sunken in the roadway and adapted to lie flush at their upper faces therewith. The runways 36 are adapted to incline upwardly 95 toward the gate if desired, to effect the depression of the runway 36 and the member 35 for operating the gate sections. 100

Each of the two gate sections is provided with a latch adapted to interlock with the 110 opposite gate section, so that the release of one latch is not sufficient to permit of the separation of the gate sections. The latch comprises a horizontal latch bar 38 pivotally supported in brackets 39 upon the outer 115 sides of the gate sections. The outer end of the latch bar 38 is provided with a depending locking finger 40 and the bar 38 is of a length adapted to project beyond the outer end bracket 39 to arrange or hold 120 the latch finger 40 beyond the adjacent bar portions of the gate body 18, of the opposite gate members, and the finger 40 with a projection 41 adapted to interlock with the adjacent bar of the opposite gate member. The 125 latch finger 40 is adapted to hang down by gravity in the interlocking engagement with the opposite hinge member, and the inner end of the latch bar 38 is provided with a double cam 42 presenting as best seen in 130

Fig. 6 upwardly and downwardly facing cam surfaces lying in the path of the free end of the adjacent operating arm 24, the latter being of sufficient length to traverse 5 adjacent cam 42 upon the initial movement of the operating arm 24, and also upon the final movement or operation thereof to release the latch 38. The finger 40 has a projection 41 extending at such an angle there- 10 to as to engage the outer bar of the opposite gate section so that the latch is automatically thrown into releasing position until the gate sections are brought into a fully closed position.

As shown in Fig. 3, the operating arms 24 and the links 25 pass through what may be termed a dead center position during the opening and closing of the gate. However, the operating arm 24 is given a continuous 20 turning movement into either an open or closed position and to prevent undue strain upon the part of the apparatus, or for slowing down the opening or closing operations of the gate, means are provided for positively connecting the gate with the outer end of the operating arm 24 at such critical times of the operation. To effect this result, each gate member is provided with inner and outer ends and at its outer portion with an upwardly flaring socket 43, which may be secured to the lower bar 15 or near thereto and onto the vertical bar 21. The free end of the operating arm 24 is preferably pointed or reduced integrally 30 so as to present inclined opposite faces so as to enter the upstanding flaring socket 43 and to bear against the opposite walls thereof in the act of directly pushing the gate members into open or closed position. It will be apparent that as the socket member 43 is rigidly mounted upon the gate member, the operating arm immediately leaves the socket member, after the critical point or time in the operation has passed.

A further feature of the invention is to provide the link 25 with an elongated slot for receiving the pin 26 at the connection of the link with the gate to permit of an initial lost motion of the link 25 relatively 40 to the gate during the swinging movement of the link 25 the arm 24 is adapted to operate the latch 40 to an extent sufficiently to release the opposite gate section; such operation takes place in connection with each latch so that the gate sections are released relatively to one another and the operating mechanism may then be brought into operation for retracting the gate or door members simultaneously.

A further feature of this invention is to provide means for cushioning the opening and closing members of the gate only at such time as the gate section reaches near its limit of its opening or closing position. To this end the weight lever 31 has

pivotedly mounted thereon one member of a dash-pot such as the cylinder 44 shown in the present embodiment. Within the cylinder 44 is a piston 45 and a rod 46 slideable through the end of the cylinder 44 and provided with an elongated slotted link 47. The dash-pot is adapted to extend upwardly from the weight lever 31 and is connected at its upper end by means of a pin 48 to the top of the wall 10 between the post 11 70 and 12. The cylinder 44 is also provided with a vent near its lower end adapted to be closed by an adjusting vent set screw 49 adapted to control the passage of air into and out of the cylinder 44.

In operation, should pressure be exerted upon one of the runways 36, one of the operating mechanisms would be placed under tension and the operating arm 24 would initially move down to release the latch 40 80 from the opposite gate section. But as the opposite side of the compressible member 35 is not under sufficient tension to operate the mechanism the other latch 40 would not be operated or released and consequently the 85 gate sections could not part. It is apparent that neither of the gate operating mechanisms could work and the gate would remain shut. The purpose of such an arrangement is to prevent the opening of the 90 gate sections should an animal of sufficient weight step on the runway 36.

When a vehicle approaches the gate and bears upon both of the runways 36 at the adjacent side of the gate, the compressible member 35 is moved downwardly uniformly 100 at opposite ends and affects the simultaneous operation of the operating arms 24 to first release the latches 40 from the gate members and to then swing the arms 24 downwardly and finally to the position shown in full and dotted lines in Fig. 3. It is apparent that as the operating arms 24 pass into their vertical positions the free 105 ends of the arms enter the coupling socket 43 and directly connect the gate sections to the operating arms. The gate sections are thus quickly moved backward into open position until the links 25 move into such angle relatively to the arm 24 as to take up 110 the finishing movement of the gate sections.

As the arm 24 swings down, the weight arm 31 is raised and the dash-pot cushioning element 44 is raised freely on the pin 48 as the latter travels in the elongated slot 120 in the link 47 and offers no resistance to the operation of the mechanism. The link 47 is of sufficient length to maintain the cushioning elements out of place until the arms 24 have reached a position near its 125 limit of movement. At such point of the operation, the pin 48 engages in the ends of the link 47 and pressure is then placed upon the piston rod 46. The opening and closing operation of the gate is therefore checked 130

only at the limits of the relative movement of the gate members. It is apparent that when the gate member is opening, the piston 45 will be pushed inwardly through the cylinder 44 and the checking of the movement depends upon the out or inflow of air through the regulator or set-screw 49.

It is of course understood that various changes and modifications may be made 10 in the details of construction and design of the above specifically described embodiment of this invention without departing from the spirit thereof, such changes and modifications being restricted only by scope of 15 the following claims;

I claim:

1. In mechanism as specified, the combination of a wall having an opening therein, a gate member slidably mounted on the 20 wall, operating means for moving the gate members into and out of the opening, a cushioning element connected to the mechanism, auxiliary means adapted to co-act with said operating means during a portion 25 of the movement of the latter to move said gate member and means associated with the cushioning element for rendering the same inactive during the major portions of the opening and closing movement, and adapted 30 to render the cushioning element active at the limit of such movement.

2. In mechanism as specified, the combination of a wall having an opening therein, a pair of gate sections mounted upon the 35 wall, operating means for such gate sections adapted to slide the same into open and closed positions, a latch mounted on each gate section adapted to engage the opposite gate section for interlocking the gate 40 sections when in closed position, means associated with the operating mechanism adapted to release said latches upon the simultaneous operation of said operating mechanism, auxiliary means carried by said 45 gate sections adapted to co-act with said operating means during a portion of the movement of the latter, and cushioning means operative only at the ends of the movements of said gate sections in either direction.

3. In apparatus as specified, the combination of a wall provided with a door or gate opening therein, a pair of door or gate sections, a pivoted operating arm for each door section, a link connecting said arm to the 55 door or gate section, said link being adapted to swing past the vertical plane of the pivotal support of the operating arm during opening and closing operation of the gate or door sections, means for connecting the door 60 or gate sections directly to the operating arm as the latter passes through the vertical plane of its pivot.

4. In an apparatus as specified, the combination of a wall having a gate or door opening therein, a door or gate section slid-

ably mounted upon the wall, an operating arm pivoted upon the wall, a link connected to the operating arm and to the door or gate section, means for actuating the operating arm to swing the latter into position at opposite sides of the vertical plane of its pivot, said link being adapted also to pass from one side to the other of the vertical plane of the pivot of the arm, a socket carried upon the door or gate section adapted to receive the free end of the arm when in lowermost position and passing through the plane of its vertical pivot.

5. In an apparatus as described, the combination of a wall provided with a door or gate opening therein, a gate section slidably mounted upon the wall, an operating arm pivotally mounted upon the wall and adapted to swing downwardly through the plane of the pivotal support of the arm, a link connecting the arm to the gate section for swinging the link through said plane, said arm extending beyond said link, and a socket fixed upon the lower portion of the door or gate section and adapted to receive the free end of said arm for directly connecting the arm to the door or gate section as the latter passes into open or closed positions, and during passage of said arm through said plane.

6. In apparatus as specified, the combination of a wall having a door opening therein, a gate section slidably mounted upon the wall, an arm pivotally mounted upon the wall, a link connecting the arm to the gate section with a pin and slot connection 100 between the link and the gate section for permitting the initial loose movement of the link, upon the gate section, means for operating the arm, a latch carried by the gate section for maintaining the same locked when 105 closed, and means associated with the arm and the latch for coöperation upon the initial movement of the arm in the opening of the gate section.

7. In apparatus as specified, the combination of a wall having an opening therein, a door or gate section slidably mounted on the wall, an arm pivoted upon the wall, a link pivoted at one end upon the arm and having a pin and slot connection with the gate 115 section at the other end, a latch carried by the gate section adapted to maintain the same normally locked when closed, and means associated with the arm and the latch for releasing the latter upon the initial lost 120 motion of the link and arm.

8. In apparatus as specified, the combination of a wall provided with a door or gate opening therein, a door or gate section slidably mounted upon the wall, an operating arm pivotally mounted upon said wall and provided with an extension, a link connecting the intermediate portion of the operating arm with said door or gate section, and with a pin and slot connection with the lat- 130

ter, a latch mounted upon the door or gate section adapted to maintain the same locked when closed and provided with a cam portion lying in the path of said arm extension, 5 and means for operating the arm whereby upon the initial lost motion of the arm to engage the latter with said cam and release the said latch prior to the opening operation of the door or gate sections.

10 9. In a closure operating device, the combination of a wall provided with an opening, a pair of closure members slidably mounted upon said wall, an operating arm pivotally secured to said wall associated with each of 15 said closure members, connections between said operating arms and said closure members, adapted to permit of initial lost motion upon the movement of said arms, interlocking latching means associated with each of 20 said closure members adapted to be released by said operating arms during said lost motion, vehicle actuated means adapted to operate said arms to open said closure members, means adapted to cushion the movement of 25 said members only at the end of such movement, and means adapted to automatically return said members to their closed position

upon the release of said vehicle actuated means.

10. In a closure operating device, the combination of a wall provided with an opening, 30 a pair of closure members slidably mounted upon said wall, an operating arm pivotally secured to said wall associated with each of said closure members, link connections between said operating arms and said closure members adapted to permit of initial lost motion upon the movement of said arms, interlocking latching means associated with each of 35 said closure members adapted to be released by said operating arms during said lost motion, vehicle actuated means adapted to operate said arms to open said closure members, means carried by said closure members adapted to co-act with said operating 40 arms during a portion of their movement, means adapted to cushion the movement of said members at the end of such movement only, and means adapted to automatically 45 return said members to their closed position 50 upon the release of said vehicle operated means.

MATTHEW C. OSTER.
